[57] CLAIM

The ornamental design for an automobile, as shown and described.

DESCRIPTION

FIG. 1 is a front pictorial view of an automobile showing my new design;

FIG. 2 is a rear pictorial view thereof;

FIG. 3 is a left side pictorial view thereof;

FIG. 4 is a top pictorial view thereof;

FIG. 5 is a front and left side pictorial view thereof;

FIG. 6 is a rear and left side pictorial view thereof;

FIG. 7 is an enlarged fragmented front and left side view thereof, similar to FIG. 5, but taken from a more frontal direction;

FIG. 8 is an enlarged fragmented rear and left side view thereof, similar to FIG. 6, but taken from a more rearward direction; and,

FIG. 9 is another enlarged fragmented front and left side view thereof, similar to FIG. 7, but showing the entire side. The right side of the automobile, not shown, mirrors the left side.
